PROCESS FOR CHLORINATING
ORTHO-CRESOL

9 Claims. (Cl. 260—521)

This invention relates to a chlorination process, more particularly for the manufacture of chlorinated phenols.

It is known to chlorinate phenols by means of chlorine or other chlorinating agents for example sulphuryl chloride, and to carry out the reaction in the presence of added catalysts in order to increase the yield of chlorinated products, or, in those instances in which more than one chlorinated product can be formed, to increase the yield of a desired product at the expense of other possible products. In particular, it has been proposed to produce an enhanced yield of the para-halo-phenol from a phenol which reacts with a sulphuryl halide to produce a mixture of ortho and para halophenols by carrying out the reaction with the sulphuryl halide in the presence of a metal halide at a temperature not in excess of 75° C. The metal halides useful for this purpose include those of aluminium, iron, tin, titanium and zinc, and particularly aluminium chloride, ferric chloride, stannic chloride, titanium tetrachloride and zinc chloride.

In the chlorination of ortho-cresol, the two principal products formed are 4-chloro-2-methylphenol and 6-chloro-2-methylphenol. Of these two compounds, the 4-chloro isomer is the more valuable as an intermediate for the manufacture of herbicidal compounds, so that methods of reducing the proportion of the undesired 6-chloro isomer are of commercial value.

In order to obtain a product containing a satisfactory proportion of the 4-chloro isomer, it is usually necessary to subject the crude chlorinated cresol to fractional distillation before further use.

The proportion of 4-chloro-2-methylphenol in the product formed by chlorinating ortho-cresol can be increased by chlorinating the ortho-cresol with sulphuryl chloride in the presence of a metal chloride. Unfortunately, when chlorocresol made in this way is used directly, without distillation, for the manufacture of other products, highly coloured impurities in the chlorocresol are retained in the final product. Consequently, the full value of this improvement in the yield of the 4-chloro isomer cannot be realised in practice because the product still requires distillation before it can be used further for the manufacture of satisfactorily light-coloured products, particularly 2-methyl-4-chlorophenoxy acetic acid and its derivatives. Moreover, when distillation of the chlorocresol is carried out in the presence of the metal chloride, tarry materials are formed with corresponding loss of chlorocresol. It would be a considerable economic advantage if this intermediate distillation could be avoided, but no satisfactory substitute for it has so far been found, particularly since the chlorocresol product tends to crystallise if kept for any length of time at or near atmospheric temperature.

2

We have now found that a surprisingly high purifying effect, sufficient to enable the resulting chlorocresol to be used satisfactorily without distillation, can be attained by carrying out the chlorination process by means of sulphuryl chloride in the presence of fuller's earth in addition to the metal halide. This purifying effect is obtainable without detriment to the catalytic effect of the metal chloride, and indeed the fuller's earth appears to have some contributive catalytic effect. An alternative adsorbent, charcoal, has been found to be quite unsuitable as a replacement for the fuller's earth in our process, since it causes the yield of chlorocresol to fall and decreases the proportion of 4-chloro cresol in the product. Also, the fuller's earth does not exert the same cleaning effect if it is added after the chlorination instead of being present during the chlorination.

Thus according to our invention we provide an improved process for the chlorination of ortho-cresol by interacting ortho cresol and sulphuryl chloride in the presence of a metal halide catalyst, wherein the interaction is carried out in the presence of fuller's earth.

The proportion of fuller's earth to be used is preferably between 0.5% and 1.0% by weight of the ortho-cresol. Larger proportions tend to produce little additional effect and smaller proportions tend to be less efficient, but they may be used if desired. Proportions of 1.5% or more tend to be less satisfactory however, since there is a tendency then for the proportion of undesirable 6-chloro-2-methylphenol in the product to increase. When the chlorination reaction is completed, the fuller's earth can be removed from the chlorinated cresol product by any convenient means, for example by settling and decantation.

The fuller's earth may be a commercial natural or activated grade, and is preferably dried before use to minimise the adverse effect of water on the metal halide catalyst.

Apart from the use of fuller's earth, the general features and conditions of the process are those already known and used in the art and no substantial modification is necessary. In particular, the reaction temperatures and the proportions of ortho-cresol, metal halide catalyst and sulphuryl chloride to be used remain substantially unchanged.

Since the melting point of ortho-cresol is about 31° C., there is a tendency for crystallisation to occur if the chlorination is carried out much below this temperature, at least in the early stages. As the yield of 4-chloro-2-methyl phenol is better at lower temperatures, it is preferred to carry out the reaction at as low a temperature as possible while avoiding crystallisation, though the actual temperature to be employed may vary for different raw materials. Usually, it is best to maintain the reaction mixture at approximately 30° C. at the start of the chlorination and to cool it progressively during the reaction to about 20° C. Higher temperatures may be used if desired, however.

The metal halide catalysts which may be used are in general, volatile metal halides, and particularly the halides of aluminium, iron, tin, titanium and zinc. The preferred metal halide catalyst is aluminium chloride, as it is a cheap material which is a very active catalyst and enables a chlorocresol of light colour and good quality to be obtained by our process with the least difficulty of operation.

Other catalysts which may be used include ferric chloride, anhydrous chloride, titanium tetrachloride and zinc chloride. The proportion of metal halide catalyst to be used is preferably between about 0.5% and 2% of the weight of the ortho-cresol, as greater proportions tend to produce little additional effect. Smaller proportions are usually suitable only when the reactants are thoroughly dried. Inert solvents or diluents may be added if desired.

The metal halide should be substantially anhydrous if a beneficial effect on the formation of the para chloro isomer is to be obtained. Likewise, the adverse effect of water on the isomer ratio of the product is preferably minimised by using substantially anhydrous materials, specially the ortho-cresol, and by excluding moisture from the reaction vessel.

Our process has the advantage of giving a chlorocresol mixture which can readily be used directly for the manufacture of other products without the need for expensive purification for example by intermediate distillation. In particular, the chlorinated cresol is very suitable for direct conversion into 2-methyl-4-chlorophenoxy aliphatic acids for example 2-methyl-4-chlorophenoxyacetic acid, by condensation with caustic soda and monochloroacetic acid and compositions derived therefrom, and yields a relatively light-coloured product. For this purpose it is not essential to remove the fuller's earth before conversion of 2-methyl-4-chlorophenoxyacetic acid, and removal after condensation is satisfactory.

The invention is illustrated but not limited by the following example in which the parts and percentages are by weight.

Example 1

297 parts of sulphuryl chloride are added over a period of 30 minutes to a mixture of 216 parts of ortho-cresol, 0.4% (i.e. 0.86 part) of anhydrous aluminum chloride and 0.5% (i.e. 1.08 parts) of activated fuller's earth (a calcium montmorillonite) which is initially at a temperature of 30° C. and is cooled gradually to 20° C. during the addition. When the addition of sulphuryl chloride is complete, the mixture is stirred for a further 2 hours, after which time stirring is stopped and the mixture is allowed to stand overnight. The resulting mixture, which may be liquid or solid, is heated during 1 hour to 70° C. and then a slow stream of nitrogen is blown through it for 2 hours to remove the acidic gases formed in the reaction. The crude chlorocresol product is then separated by decantation from most of the fuller's earth, which settles rapidly. The product is obtained in a yield of 280.9 parts and contains 92.3% of 4-chloro-2-methylphenol, 6.1% of 6-chloro-2-methylphenol, 1.5% of 4:6-dichloro-2-methylphenol and no detectable proportion of ortho-cresol (corrected infra-red analytical results). The ratio of 4-chloro isomer to 6-chloro isomer is 15, and the yield of 4-chloro-2-methylphenol is 91% of theory based on the ortho-cresol used.

Conversion of this chlorinated ortho-cresol into 4-chloro-2-methyl phenoxyacetic acid is carried out as follows:

A mixture of 142.5 parts of the above-described chlorinated ortho-cresol and 72.7 parts of monochloroacetic acid is heated to 100° C. and stirred while a slow stream of nitrogen is passed through it. 283.2 parts of an aqueous 25% solution of caustic soda are then added rapidly with continued stirring to the above mixture, the rate of addition being such that the temperature of the reaction mixtures does not exceed about 109° C. and stabilises itself when the addition is complete at about 100–103° C. The mixture is maintained at 100–103° C. for 1 hour more and then 40 parts of an aqueous 25% solution of caustic soda and 21.7 parts of molten monochloroacetic acid are added, separately and simultaneously, and the whole is stirred for a further hour at 100–103° C. while the nitrogen steam is maintained. The mixture is filtered to remove the small quantity of fuller's earth present, is then

acidified to approximately pH 6 by the addition of a small quantity of concentrated hydrochloric acid, and steam distilled to remove uncondensed materials (mainly chlorocresols). This distillation is continued until about 200 parts of distillate have been produced. The hot mixture is then acidified to approximately pH 2 by the addition of more hydrochloric acid (about 116 parts of hydrochloric acid of specific gravity 1.16 are required), and the molten layer of crude 4-chloro-2-methylphenoxy-acetic acid which is thereby formed is separated off from the aqueous layer. The aqueous layer is cooled to atmospheric temperature, and the further quantity of organic acid thus precipitated is collected, combined with the molten organic layer previously separated, and the whole is then partially dried by heating at 100–110° C. for 30 minutes. The resulting product consists of 189.4 parts of material which is found by analysis to contain 82.8±3% of 4-chloro-2-methylphenoxyacetic acid, 89.3±3% of total chloro-2-methylphenoxyacetic acids. The yield corresponds to a yield of total acids of 84.4% of theory, of which 92.7% is the 4-chloro isomer, assuming the mean value of the analyses.

The mixed acids are then neutralised with aqueous potassium hydroxide solution, 1.5% of potassium citrate is added as sequestering agent, and the solution is adjusted to pH 11.0 and to contain 32.2% of total acids (31.0±0.5% of 4-chloro-2-methylphenoxyacetic acid). This solution is slightly darker in colour than a solution prepared in a similar manner from distilled 4-chloro-ortho-cresol. Comparison of the two solutions by means of a spectrophotometer measuring the extinction coefficients at comparable dilutions (tenfold dilution), shows that the product produced by the procedure of this example is darker than the product derived from distilled 4-chloro-ortho-cresol by a factor of only 2.2.

Comparison in similar manner of (a) the product produced by the procedure of this example with (b) the product prepared using the aluminum chloride but omitting the fuller's earth, shows that the latter is darker by a factor of approximately 4.

When the conversion of the chlorocresol to 4-chloro-2-methyl-phenoxy acetic acid in the manner described in this example is repeated using chlorocresol from which the fuller's earth has not been removed, no significant difference in the colour of the product is observed.

Example 2

The procedure of Example 1 is repeated except that the anhydrous aluminum chloride is replaced by an equal weight of anhydrous zinc chloride. The procedure is also repeated using the zinc chloride but omitting the fuller's earth.

Comparison of the colour intensities of solutions of the potassium salt of 2-methyl-4-chloro phenoxyacetic acid derived from the chlorocresols so prepared shows that the product made from ortho-cresol chlorinated in the presence of zinc chloride alone is twice as dark as the product made from ortho-cresol chlorinated in the presence of zinc chloride and fuller's earth.

What we claim is:

1. A process for the chlorination of ortho-cresol which comprises reacting ortho-cresol and sulphuryl chloride at a temperature within the range of approximately 20–75° C. in the presence of from 0.5% to 2% by weight of a metal halide catalyst selected from the group consisting of the halides of aluminum, iron, tin, titanium and zinc, and from 0.5% to 1.5% by weight of fuller's earth to produce chlorinated ortho-cresol, the amounts of catalyst and fuller's earth being based on the weight of ortho-cresol.

2. Process as claimed in claim 1 wherein the fuller's earth is dried before use.

3. Process as claimed in claim 1 wherein the metal halide catalyst is aluminum chloride.

4. Process as claimed in claim 1 wherein the reaction mixture is maintained at approximately 30° C. at the

start of the chlorination and is cooled progressively during the reaction to about 20° C.

5. Process as claimed in claim 1 wherein the chlorinated ortho-cresol product is subsequently converted into a 2-methyl-4-chlorophenoxy aliphatic acid.

6. Process as claimed in claim 5 wherein the chlorinated ortho-cresol product is converted into 2-methyl-4-chlorophenoxyacetic acid, by condensation with caustic soda and monochloroacetic acid.

7. Process as claimed in claim 5 wherein the fuller's earth is not first removed from the chlorinated ortho-cresol product.

8. A process for the chlorination of ortho-cresol which comprises reacting ortho-cresol and sulphuryl chloride at a temperature within the range of approximately 20-30° C. in the presence of from 0.5% to 2% by weight of a metal halide catalyst selected from the group consisting of the chlorides of aluminum, iron, tin, titanium and zinc, and from 0.5% to 1.0% by weight, of fuller's earth, to produce chlorinated ortho-cresol, the amounts of catalyst 15

5

and fuller's earth being based on the weight of ortho-cresol.

9. The process of claim 8 wherein the chlorinated ortho-cresol product, containing some fuller's earth, is condensed with caustic soda and monochloroacetic acid to produce a 2-methyl-4-chlorophenoxy acetic acid.
